UNITED STATES PATENT OFFICE.

CORNELIUS B. CORCORAN, DECEASED, LATE OF NEW YORK, N. Y.; BY MICHAEL J. CORCORAN, ADMINISTRATOR, OF NEW YORK, N. Y., ASSIGNOR TO UNDERWOOD TYPEWRITER COMPANY, OF NEW YORK, N. Y., A CORPORATION OF DELAWARE.

TYPEWRITING MACHINE.

Application filed June 24, 1924. Serial No. 722,012.

To all whom it may concern:

Be it known that CORNELIUS B. CORCORAN, deceased, late a citizen of the United States, and late residing in the borough of Bronx, county of Bronx, city and State of New York, invented certain new and useful Improvements in Typewriting Machines, of which the following is a specification.

This invention relates to typewriting machines of the front-strike visible type in which the type-bars are hung on a curved wire, carried by a radially slotted segment, and are operated from the keyboard to deliver a whip-like stroke against the platen.

Ordinarily the blows of the type-bars are arrested, just prior to contact of the types against the platen, by a rigid stop or anvil portion of the type-bar segment acting as an interponent, to avoid the tendency of the type-bars to chatter or rebound making repeated impressions on a work-sheet; but due to the acquired momentum of the type-heads and the resiliency of the type-bars, the heads spring forward sufficiently to deliver an effective blow of the types upon a ribbon overlying the work-sheet.

Such impact between the metallic surfaces of the type-bars and integral or anvil surface of the segment produces a clattering noise of such intensity as to constitute an annoyance, and it is, therefore, one of the features of the present invention to provide improved means for minimizing such metallic sounds and still maintain the advantages of an effective rigid segmental anvil or type-bar stop.

There is provided a stop or anvil that is moderately yieldable, tending to reduce the shock of the type-bars and prevent the impact of the blow from being transmitted to the other parts of the machine, thus further reducing the noise, and the wear. The simple and inexpensive type-bar stop can be readily applied without changes in a machine. These features are accomplished by securing a segmental stop upon the level upright face of the segment in which the type-bars are pivoted, ordinarily utilizing openings which exist therein for attaching purposes, the stop having one or more rows of raised surfaces for type-bar contact and being provided with sound-reducing ele-

ments proven by use to be effective. More than one embodiment is shown as illustrative of the general spirit of the invention, which is not limited, however, by the exact constructions indicated.

Other features and advantages will hereinafter appear.

In the accompanying drawings,

Figure 1 is a front elevational view of a type-bar segment, as applied to a machine of the Underwood type, showing the application of an embodiment of the invention, the platen appearing in dot-and-dash lines.

Figure 2 is a transverse sectional view of the same, the section being taken on line 2—2 of Figure 1, and the type-bar shown in full lines, as connected to the segment in a rest position, the bar being also shown in a raised position in dot-and-dash lines.

Figure 3 is a view similar to Figure 1, but drawn to a smaller scale, and showing a modified form of stop.

Figure 4 is a transverse sectional view taken on line 4—4 of Figure 3 and drawn to an increased scale.

Figure 5 is a view like Figure 3, showing a further modification in the stop construction.

In the drawings only such parts of a typewriting machine are shown as relate directly to the invention, the other parts being of ordinary well-known construction, unaffected by and unrelated to this disclosure. The platen, designated by the numeral 10, is of the revolute cylindrical type mounted to shift into upper and lower case positions to receive an impact from either of the type-characters carried on the type-heads 11, the same being fixed on the free ends of type-bars 12, pivoted on an arcuate rod 13, and actuated by links 14 engaging the bars near their pivoted ends.

The type-bars shown are of the Underwood pattern, and the links 14, as will be readily understood, are moved by their connection with key-actuated levers on the keyboard (not shown) in the ordinary manner. The pivot-rod 13 is housed in the lower part 100 of a type-bar segment 15 having slots 16 to guide the type-bars, and an extending integral rib 17 clearing the type-bars at the end of their operative stroke. The segment

is fixed by screws 18 to the front part of the typewriting machine frame, indicated at 19, the construction being well known.

As shown in Figures 1 and 2, there is secured to the flat level upright face 20 of the segment 15 an arcuate stop 21 formed from a strip of spring-tempered, hard metal having rounded ends and being provided with radially-extending lugs 22 near its ends, at its convex lower edge, through which pass headed binding screws 23 holding the segmental stop 21 firmly upon the face of the segment 15.

Formed in the stop or anvil, is a groove 15 or recess 24 extending from end to end thereof and presenting a moderately yieldable convex upper surface for arresting the type-bars just prior to the impact of the types against the platen, as can be seen in Figure 2.

It is to be understood, however, that the type-heads will continue in their movement until an impression has been made on the work-sheet through a ribbon (not shown), the stop 21 acting to prevent chattering of the type-head, and to reduce the noise occasioned by the impact of the type-bar against a positively rigid, unyielding surface, such as the segment face direct.

In the modification illustrated in Figures 3 and 4, a plate of flexible metal is used for the stop 25, the same being formed to present two outstanding hollow ribs 26 and 27 raised from the face 20 of the segment, to which the plate 25 is attached by screws 28 passing through plate-extensions 29, equivalent to the lugs 22, as previously described.

The ribs are spaced concentrically with the contour of the plate and segment, and their concave under surfaces have secured to them a filler 30 of relatively soft yielding material, as felt, a layer 31 of which is interposed between the entire under surface of the plate and the face 20 of the segment, as can be seen in Figure 4. The felt lining acts as an effective sound-absorbent, eliminating the emission of sound caused by impact of the type-bar against the ribs, and materially softens the blow of the type-bar without affecting the desired result obtained by the anvil-ribs.

As a further means for preventing sound from issuing, the plate 25 may have in its lower convex portion a plurality of slits or incisions 32 (Figure 5), arranged radially in spaced relation, and extending inwardly from the edge nearly to the lower rib 27, this comb-like structure effectually breaking the sound-waves and rendering the machine substantially noiseless so far as the type impact is concerned.

The recesses 33 in the devices shown in Figures 3 and 5 are merely to clear certain

parts of the typewriting machine mechanism, and have no purpose relative to the invention.

Variations may be resorted to within the scope of the invention, and portions of the improvements may be used without others.

Having thus described the invention, I claim:

1. In a typewriting machine, the combination with type-bars and a support-segment to which the type-bars are pivoted, of a spring stop to arrest the type-bars at their impression strokes, said stop comprising a plate shaped to be seated on the level upper portion of the segment and having concentric raised hollow ribs extending throughout its length, noise-absorbent material carried in the rib cavities and disposed over the under surface of the plate, and means for securing the stop on the segment.

2. In a typewriting machine, the combination with type-bars and a support to which the type-bars are pivoted, of a stop to arrest the type-bars at their impression strokes, said stop being comprised of spring material shaped to conform with the support and having one or more raised longitudinal ribs, a felt filler fixed in the rib cavities, a felt sheet interjacent the stop and support, and means for fastening the stop upon the face of the support.

3. In a typewriting machine, the combination with type-bars and a support to which the type-bars are pivoted, of a stop to arrest the type-bars at their impression strokes, said stop being comprised of spring material shaped to conform with the support and having one or more raised longitudinal ribs, a felt filler fixed in the rib cavities, a felt sheet interjacent the stop and support, said stop having a plurality of slits in its lower edge, and means for fastening the stop to the face of the support.

4. In a typewriting machine, the combination with type-bars and a support to which the type-bars are pivoted, of a stop to arrest the type-bars at their impression strokes, said stop consisting of a plate, raised hollow ribs formed integrally on the plate and extending substantially its full length, a plurality of radial incisions extending in from the lower edge of the plate, means to secure the stop upon the level central surface of the support, a sound-absorbent filler for the ribs, and a sound-absorbent lining interposed between the stop and support.

MICHAEL J. CORCORAN,
Administrator of the estate of Cornelius B. Corcoran, deceased.
